US0D1026655S

(12) **United States Design Patent** (10) **Patent No.:** **US D1,026,655 S**
(45) **Date of Patent:** ** *May 14, 2024

(54) **BOTTLE SHOULDER**

(71) Applicant: **Conopco, Inc.**, Englewood Cliffs, NJ (US)

(72) Inventors: **Laurent Jean-Marie Hainaut**, Bearsville, NY (US); **Heesop Chong**, Staten Island, NY (US); **Mariana Escobar Jimenez**, Brooklyn, NY (US)

(73) Assignee: **Conopco, Inc.**, Englewood Cliffs, NJ (US)

(*) Notice: This patent is subject to a terminal disclaimer.

(**) Term: **15 Years**

(21) Appl. No.: **29/762,915**

(22) Filed: **Dec. 18, 2020**

(51) **LOC (14) Cl.** **09-01**

(52) **U.S. Cl.**

USPC **D9/516**; D9/558

(58) **Field of Classification Search**

USPC D9/500-505, 529, 547, 548, 549, 550, D9/556, 557, 558, 573, 575, 428, 445, D9/518, 551, 563, 564, 520, 449, 718, D9/724, 754, 686, 688, 690, 682, 684, D9/692, 448, 689, 697, 560, 687, 694, D9/691, 516; D3/203.2; D18/56; D28/85, 58

CPC .. B65D 1/0223; B65D 83/205; B65D 1/0246; A45D 34/045

(57) **CLAIM**

The ornamental design for a bottle shoulder, as shown and described.

DESCRIPTION

FIG. 1 is a perspective view from above and one side;

FIG. 2 is a front elevational view;

FIG. 3 is a rear elevational view;

FIG. 4 is a side elevational view;

FIG. 5 is an elevational view of the other side;

FIG. 6 is a top plan view; and,

FIG. 7 is a bottom plan view.

The broken lines in the figures illustrate portions of the bottle shoulder that form no part of the claimed design.

1 Claim, 5 Drawing Sheets
